UNITED STATES PATENT OFFICE

WALTER D. HALL, OF PORT HURON, MICHIGAN.

TROLLEY-WIRE CLAMP.

1,161,474.

Specification of Letters Patent.

Patented Nov. 23, 1915.

Application filed September 20, 1913. Serial No. 790,865.

To all whom it may concern:

Be it known that I, WALTER D. HALL, a subject of the King of Great Britain, residing at Port Huron, in the county of St. Clair and State of Michigan, have invented certain new and useful Improvements in Trolley-Wire Clamps, of which the following is a specification.

My invention relates to improvements in trolley wire clamps and particularly to a device of this character to be supported or suspended by wire or wires extending longitudinally or transversely of the trolley wire or track.

An important object of this invention is to provide a device of the above mentioned character, formed of few and simple parts, which may be readily assembled and separated, and will not be liable to accidents, such as the disconnection of the parts thereof or of the trolley wire held by the same.

A further object of this invention is to provide a trolley wire clamp, which may be used in connection with either a trolley wheel or sliding shoe contact device.

A further object of the invention is to provide a device of the above mentioned character, which can be assembled, installed, or taken apart without loss of time, can be manufactured at a small expense, and is durable under the conditions usually found where a catenary or other trolley wire construction is employed.

Other objects and advantages of this invention will be apparent during the course of the following description.

In the accompanying drawings forming a part of this specification and in which like numerals are employed to designate like parts throughout the same, Figure 1 is a perspective view of the clamp, Fig. 2 is a transverse sectional view taken on line 2—2 of Fig. 1, showing the trolley and suspension wires held thereby, Fig. 3 is a side elevation of the clamp with the transverse bolt in section, Fig. 4 is an elevation of the inner side of one of the clamping members, showing a suspension strap employed in connection therewith, Fig. 5 is a perspective view of the transverse bolt, and, Fig. 6 is a similar view of the suspension strap, the upper portion thereof being broken away.

In the drawings, wherein for the sake of illustration, is shown a preferred embodiment of my invention, the numeral 10 designates my improved trolley wire clamp as a whole, comprising oppositely arranged clamping plates 11, which are identical. At their lower ends the clamping plates 11 are provided with recesses 12, forming contracted jaws 13 to hold a portion of a trolley wire 14, as shown. At their upper ends, the clamping plates 11 are provided with outwardly curved or bulging heads 15, provided with spaced inwardly extending aligned clamping teeth or ribs 16. The outwardly bulging heads 15 provide a relatively large chamber or opening 17, to receive a suspension wire 18, extending longitudinally of the track and in the same vertical plane with the trolley wire 14. The outwardly bulging heads 15 are provided upon their adjacent inner edges with openings or recesses 19, which are in registration, for forming a common vertical opening for receiving a suspension strap, to be referred to. At this point, attention is called to the fact that the clamping plates 11 are permanently spaced providing an opening 20 therebetween when the trolley wire is inserted between the lower jaws.

One clamping plate 11 is provided through its central portion with a transverse opening 21, which is square in cross-section to receive a square portion 22 of a transverse clamping bolt 23. This clamping bolt is provided with a screw-threaded end portion 24, extending outwardly beyond the opposite clamping plate 11. Arranged upon the screw-threaded portion 24 is a nut 25, engaging a washer 26. As shown in Fig. 2, the clamping bolt 23 serves to clamp the plates 11 into engagement with the suspension wire 18 and the trolley wire 14 whereby these plates may be readily separated and assembled by proper manipulation of the single clamping bolt.

It is often desirable to suspend the trolley clamp by means of a strap 27, which may be inserted through the vertical opening or openings 19, to extend into the space 20, as clearly shown in Fig. 4. The strap 27 is provided at its lower end with an opening 28 to receive the clamping bolt 23. The strap 27 is provided at its upper end (not shown) with suitable means whereby the same may be connected with transverse suspension wires or other supporting means.

In the use of the trolley clamp, the same may be suspended by either the longitudinally extending cable 18 or the strap 27. In

either case the trolley wire 14 is gripped between the jaws 13 and is suspended thereby. The clamping plates 11 are drawn together by proper manipulation of the nut 25.

5 It is to be understood that the form of my invention herewith shown and described is to be taken as a preferred example of the same, and that various changes in the shape, size and arrangement of parts may be resorted to without departing from the spirit of the invention or the scope of the subjoined claim.

Having described my invention, I claim:—

15 A trolley wire clamp and suspension device, comprising a pair of separate oppositely arranged plates provided substantially centrally thereof with aligned transverse openings and at their upper ends with

inwardly projecting extensions having recesses formed therein which are in registration and at their lower ends with clamping jaws to engage a trolley wire, a single bolt passing through the transverse openings to bind the plates together against separation, and a strap arranged within the recesses, and serving to prevent one plate from being turned upon the bolt with relation to the other and having its end apertured to receive the bolt.

20 In testimony whereof I affix my signature 30 in presence of two witnesses.

WALTER D. HALL.
